UNITED STATES PATENT OFFICE.

JOSEPH F. L. UHL, OF TOLEDO, OHIO, ASSIGNOR TO THE TOLEDO METAL FURNITURE COMPANY, OF TOLEDO, OHIO, A CORPORATION OF OHIO.

KNOCKDOWN STAND, STOOL, OR THE LIKE.

1,023,181.

Specification of Letters Patent. Patented Apr. 16, 1912.

Application filed July 17, 1911. Serial No. 638,881.

To all whom it may concern:

Be it known that I, JOSEPH F. L. UHL, a citizen of the United States, and a resident of Toledo, in the county of Lucas and 5 State of Ohio, have invented a certain new and useful Knockdown Stand, Stool, or the Like; and I do hereby declare the following to be a full, clear, and exact description of the invention, such as will enable others 10 skilled in the art to which it appertains to make and use the same, reference being had to the accompanying drawings, and to the figures of reference marked thereon, which form a part of this specification.

15 My invention relates to metal furniture, and particularly to the construction of metal stools, stands or other similar articles of the knockdown type, but is not restricted to such use.

20 The object of my invention is the provision of an improved article of furniture of this character, which is simple, strong and durable in its construction, inexpensive of manufacture, and capable of having the 25 parts thereof easily and quickly assembled in set up form or separated and compactly packed for storing, shipping, or the like.

The invention is fully described in the 30 following specification and while, in its broader aspect it is capable of embodiment in numerous forms, a preferred embodiment thereof is illustrated in the accompanying drawings, in which,

Figure 1 is a perspective view of a stand 35 embodying my invention with a water-cooler supported thereby. Fig. 2 is an enlarged inner view of portions of a leg and the top ring of the stand in engagement, and Figs. 3 and 4 are sections on the lines 40 $x-x$ and $y-y$ in Fig. 2.

Referring to the drawings, 1 designates the legs, 2 the top rim or member, and 3 the leg bracing member of a stand, stool or the like embodying my invention. The top 45 member 2 is preferably formed of a narrow strap-like strip of sheet-metal, which is bent into a ring or other shape, as may be desired, with its ends fastened together in any suitable manner, as at 4, and has its lower 50 edge rolled inwardly to provide a ledge or flange 5 therein upon which a water-cooler 6 or other article may rest. Each of the legs 1 comprises a strip of sheet-metal which is preferably of U or channel shape in cross-

section, with its channel disposed inwardly, 55 and has its upper end portion flattened or substantially so, as at 7, to adapt it to rest flatwise against the outer side of the member 2. To adapt the legs to separably support the member 2 the flattened portion 7 60 of each, which bears against the member side, is offset outwardly from the body or subjacent portion of the leg to form a shoulder 8, which is preferably tapered or slightly inclined, as indicated, for the purpose hereinafter described. The upper 65 ends of the leg portions 7 are bent inwardly preferably in hook shape, as shown at 9, to adapt them to engage over the upper edge of the member 2. The upper edge of the 70 member 2 is preferably provided with equidistantly spaced notches 10 for the hooked ends 9 of the legs to seat in, so that the upper ends of the legs and the top edge of the member 2 will be substantially flush, as 75 shown. The hooks 9 and shoulders 8 of the legs are so spaced that when the former are hooked over the upper edge of the member 2 and the lower end portions of the legs then forced inward to proper upright position 80 the shoulders 8 thereof will be forced under the rounded lower edge of said member and exert a wedge-like action thereon in opposition to the hooks 9, thus causing the member to be firmly gripped between 85 the shoulders and hooks 9 of the legs. The member 3 which holds the legs in locked engagement with the member 2 is shown in the present instance as being formed of 90 strap-metal which is bent in rectangular 95 form with the corners thereof looped outward to project within the leg channels and engaged over studs or hooks 11 in said channels, as indicated.

It is evident that to assemble a stand, stool 95 or the like constructed in accordance with my invention, it is only necessary to engage the upper hooked ends 9 of the legs over the upper edge of the member 2 within the notches 10, if such notches be provided in 100 said member, and then to draw the legs inwardly to set up position so as to force the shoulders 8 thereof under the lower flanged edge of the member 2 whereby such member is firmly engaged between the shoulders 8 105 and hooks 9 of the legs. When the legs have been placed in such position the tying member 3 is slipped down over the studs.

11 within the leg channels to prevent an outward movement of the legs until released by said member.

It is apparent that this forms a very simple, light and cheap construction of stand for water-coolers or other articles, or for stools or the like, and is capable of being easily and quickly set up or knocked down as desired.

10 I wish it understood that my invention is not limited to any specific construction or arrangement of the parts except in so far as such limitations are specified in the claims.

15 Having thus described my invention, what I claim as new and desire to secure by Letters Patent, is,—

1. In an article of the class described, a top member, legs for said member having 20 their upper ends provided with opposing portions which coöperate to grip said member when one portion is engaged to said member and the legs are drawn inwardly to set up position, the lower of said portions 25 having wedge-like coaction with the top member when the legs are drawn inwardly, and means for securing the legs in locked engagement with said member.

2. In an article of the class described, a 20 top member, channeled metallic legs for said member, said legs having their upper end portions flattened to conform in cross-section to the shape of the coacting portions of said member and provided with opposing shoulders which coöperate to grip said member when one shoulder is engaged over the same and the legs are drawn inward to set-up position, and means for securing the legs in locked engagement with said member.

3. In an article of the class described, a rim having an inturned flange at its lower edge, legs having their upper ends hooked

for engaging over portions of the rim and having shouldered portions adjacent 45 said hooked portions for wedge-like engagement with the lower flanged edge of the rim when the legs are drawn inwardly from extended position with their hooked portions in engagement with the rim, and 50 means separately attached to the legs for retaining the same in rim gripping position.

4. In an article of the class described, a rim formed of strap-metal and having its 55 lower edge rolled inwardly to form an article supporting ledge, canneled legs having their upper end portions flattened to lie against the outer side of the rim and having portions hooked over the rim and portions extending under the rim to support the 60 same, and means separately attached to the legs below said rim to retain the same in gripping engagement with the rim, said legs being adapted when released by said means and swung outwardly relative to the 65 rim to release the latter.

5. In an article of the class described, a top rim member, legs for such member having 70 their upper ends adapted to separably engage portions thereof and also having subjacent portions which, when the legs are drawn inwardly from laterally extended position relative to the rim with their upper ends in engagement with the rim, co-operate with said leg ends to securely grip 75 the rim, and means separably attached to the legs for holding the same in rim gripping position.

In testimony whereof, I have hereunto signed my name to this specification in the 80 presence of two subscribing witnesses.

JOSEPH F. L. UHL.
